UNITED STATES PATENT OFFICE

171,213

PANTY OR SIMILAR ARTICLE

Egon Kudelka, New York, N. Y.

Application July 7, 1953, Serial No. 25,827

Term of patent 7 years

(Cl. D3—17)

To all whom it may concern:

Be it known that I, Egon Kudelka, a citizen of the United States of America, residing in New York city, county of New York, and State of New York, have invented a new, original, and ornamental Design for a Panty or Similar Article, of which the following is a specification, reference being had to the accompanying drawing, forming part thereof, wherein,

I claim:

The ornamental design for a panty or similar article, substantially as shown.

EGON KUDELKA.
